UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

SHOCK-ABSORBING MECHANISM.

Application filed May 28, 1924. Serial No. 716,304.

This invention relates to improvements in shock-absorbing mechanisms.

One object of the invention is to provide a spring plate shock-absorbing mechanism especially adapted for railway draft riggings, wherein are obtained high capacity and easy release.

Another and more specific object of the invention is to provide a spring plate shock-absorber having the ends of the springs enlarged and rounded so as to minimize the amount of wear between said ends and those parts of the shock-absorbing mechanisms engageable therewith and prevent gouging of those parts, thus increasing the longevity of said mechanisms.

Other objects and advantages of the invention will more clearly appear from the description and claims hereinafter following.

In the drawings forming a part of this specification, Figure 1 is a horizontal, longitudinal sectional view of a portion of a railway draft rigging, showing my improvements in connection therewith. Figure 2 is a vertical, longitudinal sectional view corresponding to the section line 2—2 of Figure 1. Figure 3 is a perspective view of one of the spring plate elements. And Figure 4 is a horizontal, longitudinal sectional view of a modified form of spring shock-absorbing mechanism.

In the modification shown in Figures 1, 2 and 3 of the drawings, 10—10 denote channel-shaped draft sills of a car under-frame, to the inner faces of which are secured front stop lugs 11 and rear stop lugs 12. A portion of the draw-bar is indicated at 13, the same being operatively associated with a hooded cast yoke 14, within which is disposed the shock-absorbing mechanism proper. The yoke and parts therewithin are supported in operative position by a detachable saddle plate 15.

The improved shock-absorbing mechanism proper, as shown, comprises, broadly, two end casings A—A; an intermediate casing B; four groups of spring plates C; and front and rear followers D—D; all of said parts being retained within the yoke 14.

Each of the casings A is of hollow rectangular form having a transverse end wall 16 provided with a convex bearing surface

on its interior and provided with top and bottom parallel walls 18—18 and side walls 17—17.

The intermediate casing B is provided with top and bottom parallel walls 20—20 and side walls 19—19. Within each of the end casings A are arranged a group of 60 spring plates C, and within the intermediate casing B is arranged a pair of groups of spring plates C, the adjacent groups of plates being separated by spacer blocks, the blocks 22 being movably arranged between the intermediate casing and the end casings and having oppositely disposed concave bearing surfaces, while the block 21 is formed integrally with the intermediate casing B centrally thereof and is provided with 70 opposed convex bearing surfaces.

The spring plates C are preferably made of spring steel and upon relative approach of the followers D, it is apparent that the plates will tend to be flexed about the bearing blocks and create friction between the plates. The opposed inner ends of the adjacent casings are normally separated a distance corresponding to the permissible compression stroke of the mechanism. With this arrangement, upon a full compression stroke, it is evident that the casings A—A and B will abut each other, and simultaneously therewith the plates will be substantially at their limit of flexure.

Heretofore, where spring plates have been used, it has been the tendency for the relatively sharp and generally "raw" ends of the plates to wear through or badly gouge the opposed surfaces of the co-operating parts of the shock-absorbing mechanism with which they slidably engage. This has been extremely objectionable and in order to overcome this defect, I have so formed the ends of my spring plates that these ends do not present any sharp cutting edges that may wear on the co-operating members. Each of the spring plate elements is folded transversely at its center line substantially in the shape of a U, the parallel legs 23 being spaced apart a distance substantially equal to the thickness of the material of the plates and being connected at one end, which I term the head end, by a curved portion 24.

In assembling the springs in place, the alternate springs are arranged with their free

ends extending in opposite directions transversely of the center line of the mechanism, the legs of one plate member slidably straddling a leg of the adjacent plate member.

5 Thus it is seen that the plate members are arranged in pairs, the head ends of the adjacent members being arranged on alternate sides of the longitudinal center line of the casing.

10 In the modification shown in Figure 4, A'-A' indicate the end casings provided with inwardly extended convex bearings 116, and B' indicates the central casing having a double-convex bearing block 121 integral therewith. The spring plate members C' are arranged within the casings, and double-concave spacer blocks 122 are interposed between the adjacent groups of spring plate members between the end casings and the intermediate casing. In this modification, the spring plates have their parallel legs 123 brought closely together and are connected by an enlarged head end 124 so as to form a loop at said head end.

25 In assembling, the adjacent spring plate members are arranged transversely of the casing members, the head ends of the adjacent spring plate members lying on opposite sides of the longitudinal center of the casing, the head ends of the alternate plates being substantially in contact.

30 In both the modifications shown, it will be seen that transverse shifting of the spring plates relative to one another is to a large extent prevented, inasmuch as there is an interlocking relation between them, and the head ends held in place by the housings.

I have herein shown and described what I now consider the preferred manner of carrying out my invention, but the same is merely illustrative, and I contemplate all changes and modifications that come within the scope of the claims appended hereto.

I claim:

45 1. In a spring shock-absorbing mechanism, a spring resistance comprising a plurality of separate plate springs adapted to be arranged transversely across said mechanism, each of said springs being folded in the middle and arranged with the folded portions on alternately opposite sides of the longitudinal center of said mechanism, the portions of said plates opposite the folded portions being arranged to abut the adjacent folded portions to restrain movement thereof past; and means for transmitting shock to said springs to flex the same.

2. In a shock absorbing mechanism, the combination with means providing spaced walls extending in substantially parallel relation; of a plurality of relatively movable spring plates disposed between said walls and extending at an angle thereto, said plates including raw unfinished ends on certain of them, which ends are disposed in

proximity to said walls, and rounded portions on adjacent plates interposed between the raw ends and the aforesaid walls, said raw ends abutting said rounded portions to prevent travel of said raw ends past said rounded portions into engagement with said walls.

3. In a spring shock-absorber, a plurality of plate springs arranged transversely across said mechanism each of said plates being bent to form a pair of substantially parallel legs and connecting head, with the head of one plate adjacent the end of the leg of an adjacent plate and extending outwardly therebeyond, means for supporting said plate springs for operation; and means for transmitting shocks to said plate springs in a direction to flex the same.

4. In a spring shock-absorber, a spring resistance comprising a plurality of plate springs, each bent to form a pair of legs connected at one end by a head, and arranged with the legs of one spring of a pair of adjacent springs straddling a leg of the other co-operating spring; and means arranged to flex said springs upon the application of pressure to said means.

5. In a spring shock-absorber, the combination with supporting mechanism; of a plurality of plate springs adapted to be arranged transversely across said mechanism, each of said plates being bent to substantially U-shaped form, the legs of the springs being spaced apart a distance substantially equal to the thickness of the material of the springs, said springs adapted to be arranged within said shock absorber with the legs of the adjacent springs extending in opposite directions, and the legs of one spring slidably straddling a leg of the other spring, and means arranged to flex said spring plates upon application of pressure to said means.

6. As an article of manufacture, a spring plate for use in a spring gear, said plate being folded in the middle to form a pair of adjacent substantially parallel legs and an integral rounded connecting portion at one end of said legs.

7. In a shock absorbing mechanism, the combination with means providing spaced walls; of a plurality of spring plates having their end portions disposed in proximity to said walls, the ends of certain of said plates on opposite sides of the mechanism having connecting portions, and other ends of said plates being flat, the flat portions of said plates being arranged in line with and inwardly of the connecting portions of the adjacent plates and abutting thereagainst; and means for flexing said spring plates upon application of pressure to said means.

8. In a shock absorbing mechanism, the combination with means providing spaced

- walls; of a plurality of adjacent relatively movable spring plates, including raw, unfinished edges disposed in proximity to said walls; and means associated with said spring plates to restrain movement of said raw edges into engagement with said walls, said means consisting of connecting portions for certain of said plates which portions are interposed between said raw edges and said walls; and means for flexing said spring plates upon the application of pressure to said means.
9. In a shock absorbing mechanism, the combination with an intermediate casing, and co-operating end casings arranged to be movable relative to said intermediate casing; a plurality of spring plates disposed in said intermediate casing; a plurality of spring plates disposed in said end casings; spacing means for flexing said springs, including spacing elements interposed between the springs in the end casings, and the springs in the intermediate casing; followers; and yoke means encircling the mechanism and adapted to flex said springs upon movements in opposite directions.
10. In a shock absorbing mechanism, the combination with intermediate and end casings providing spaced wall surfaces; a plurality of spring plates disposed in each of said casings, said springs having unfinished end portions disposed in proximity to said wall surfaces; means associated with said springs for restraining movement of said unfinished edges into engagement with said wall surfaces, said means being interposed between the unfinished ends of said springs and said wall surfaces and presenting rounded bearing faces for engagement with said wall; yoke means encircling said mechanism; and means for flexing the springs in said casings upon movement of said yoke means in opposite directions.

In witness that I claim the foregoing I have hereunto subscribed my name this 7th day of May 1924.

JOHN F. O'CONNOR.
